(57) **CLAIM**

The ornamental design for a nail file as shown and described.

DESCRIPTION

FIG. 1 is a top, front and right perspective view of a nail file showing my new design;

FIG. 2 is a front elevational view thereof;

FIG. 3 is a rear elevational view thereof;

FIG. 4 is a right view thereof;

FIG. 5 is a left view thereof;

FIG. 6 is a top plan view thereof;

FIG. 7 is a bottom plan view thereof; and

FIG. 8 is an exploded perspective view, showing the sheath in a partly detached position from the nail file; and, FIG. 9 is another exploded perspective view, showing the sheath in a completely detached position from the nail file. The evenly-spaced broken lines illustrate portions of the nail file that form no part of the claimed design.
